UNITED STATES PATENT OFFICE.

FRANK F. ARNOLD AND CONRAD KESTEL, OF NEW YORK, N. Y.

RAZOR-BLADE KNIFE.

Application filed October 9, 1925. Serial No. 61,572.

This invention relates to razor blade knives, an object of the invention being to provide a simple, inexpensive construction of device which will firmly hold a safety razor blade and permit the use of the same as a knife or as a holder for permitting the convenient honing of the blade.

A further object is to provide a blade holder, consisting of but two parts, which can be conveniently assembled and taken apart, which is neat and attractive in appearance, inexpensive to manufacture, and strong and durable in use.

With these and other objects in view, the invention consists in certain novel features of construction and combinations and arrangements of parts which will be more fully hereinafter described and pointed out in the claims.

20 In the accompanying drawings—

Figure 1 is a plan view of our improved device;

Figure 2 is a view in longitudinal section on the line 2—2 of Figure 1;

25 Figure 3 is a view in side elevation of the blade holder, showing the same in expanded position.

Our improved device comprises two separable parts, namely, a blade holder A and handle B, the blade holder adapted to clamp and securely hold a safety razor blade C.

The blade holder is composed of a single piece of metal having sufficient resiliency, and which is formed as follows: The strip or piece forming the blade holder is bent intermediate its ends, forming a loop 1 which is desirable to give the necessary resiliency or spring action to the blade holder. From the loop 1 the piece or strip is flat for the desired length, forming blade clamping plates 2 and 3, and from the plates 2 and 3 the ends of the strip or piece are curved transversely, as shown at 4, while the extremities of the strip or piece are laterally offset, forming lateral projections 5, 5.

One of the blade clamping plates 2, is made with openings 6, and projections 7 are formed on the other blade clamping plate 3, so that when the razor blade C is inserted between these plates 2 and 3 and the latter are forced toward each other, the projections 7 will project through the openings ordinarily found in a razor blade and also through the openings 6 in the opposite plate 55 to hold the blade securely in place.

The handle B is cylindrical in form and preferably constitutes a length of tubular metal, although of course it may be of any suitable material. This handle B is formed with aligned openings 8, 8 in its opposite walls which are so located as to receive the offset portions 5, 5 of the blade clamp A. The transversely curved portions 4, 4 of member A are of such size as to fit within the tubular handle B when they are forced 65 toward each other, as indicated clearly in Figure 2.

The operation is as follows:

When the blade C is inserted in position between the plates 2 and 3, the member A is 70 compressed; in other words, the sections or portions 4, 4 are forced toward each other and are held in this position and inserted into the handle B until the laterally offset portions 5, 5 reach the openings 8, 8, when 75 such portions 5 will spring into the openings and serve to hold the members A and B securely coupled together.

To uncouple the members, the thumb and finger may be utilized to compress the laterally offset portions 5, 5 inwardly, when the blade clamp can be removed from the handle. A strong pull on the blade clamp or holder 80 relative to the handle will also effect a release of the parts.

85 Various slight changes and alterations might be made in the general form of the parts described without departing from our invention, and hence we do not limit ourselves to the precise details set forth but consider ourselves at liberty to make such slight 80 changes and alterations as fairly fall within the spirit and scope of the appended claims.

We claim:

1. A razor blade knife, including a tubular handle and a blade holder consisting of a single member bent intermediate its ends and forming blade clamping plates adjacent the intermediate bent portion, the extremities of said member being curved transversely and adapted to fit within the tubular handle, said handle having openings in its opposite walls, and laterally offset portions on the blade holder adapted to spring into said openings and hold the parts coupled together. 100

2. A razor blade knife, including a tubular handle and a blade holder consisting of a single member bent intermediate its ends and forming blade clamping plates adja- 110

cent the intermediate bent portion, the extremities of said member being curved transversely and adapted to fit within the tubular handle, said handle having openings in its opposite walls, and laterally offset portions on the blade holder adapted to spring into said openings and hold the parts coupled together, one of said blade engaging plates

having openings therein, and projections on the other of said blade engaging plates 10 adapted to project through openings in the blade and into the openings of the first-mentioned plate.
